UNITED STATES PATENT OFFICE

2,461,763

TANK ROOF

Paul Offenhauser, Houston, Tex.

Application February 12, 1946, Serial No. 647,105

2 Claims. (Cl. 220—26)

1

This invention relates to a tank roof.

An object of the invention is to provide a roof or cover of the character described which has been specially designed for use in connection with large storage tanks, particularly tanks for storing oil.

It is another object of the invention to provide a tank roof of such construction that it will float on the liquid in the tank and readily rise and fall with the liquid level without injuring the tank or room and while constantly maintaining a seal to prevent the escape of vapors from the oil in the tank.

It is a further object of the present invention to provide a floating tank roof which will adjust itself to a tank out of plumb and at the same time maintain a perfect seal to prevent the escape of said vapors.

It is a still further object of the present invention to provide a tank roof of the character described which is very flexible.

Other advantages will be apparent from the following specification which is illustrated in the accompanying drawings, wherein—

Figure 1 is a fragmentary vertical sectional view of a tank showing the roof in section.

Figure 2 is an enlarged fragmentary transverse sectional view taken on the line 2—2 of Figure 3.

Figure 3 is a transverse sectional view taken on the line 3—3 of Figure 1.

Figure 4 is an enlarged fragmentary sectional view taken on the line 4—4 of Figure 5, and

Figure 5 is an enlarged vertical sectional view taken on the line 5—5 of Figure 3.

Referring now more particularly to the drawing wherein like numerals of reference designate the same parts in each of the figures the numeral 1 designates the tank proper which may be of any conventional construction and which has the bottom outlet connection 2.

The numeral 3 designates the vertical outer wall of a trough forming a portion of the roof. The wall is of cylindrical contour and has an outwardly turned annular flange 4, at its lower end. The numeral 5 designates the inner wall of the trough. This inner wall diverges upwardly and inwardly from the outer wall and, at its lower end, is welded to the outer wall.

The inner wall of the trough is of a frustoconical contour. This trough is maintained entirely or partly filled with a suitable liquid, preferably a liquid that is unaffected by changes in temperature. Opposite the trough are the shoes 6 which extend entirely around the tank 1 and whose side margins overlap as shown in Figure 4.

These shoes are shaped to conform to the contour of the tank wall and surrounding the tank and located between it and the trough there are the flexible upper and lower tubes 7 and 8 formed of rubber or similar material and having relatively stiff walls so as to tend to maintain a shape which is circular in cross section contour.

When assembled with the roof and located within the tank the tubes are under pressure, as in Figure 1, and are substantially elliptical in shape in cross section. The trough hereinabove referred to is connected to the shoes 6 by links, as 9, there being, preferably, two links to each shoe. The ends of these links have eyes which are linked with similar eyes of the brackets 10, 11. The brackets 10 are secured to the outer wall 5 of the trough and the brackets 11 are secured to the corresponding shoes 6 so that the roof may sway back and forth depending on the swaying movements of the tank.

Inside of the trough there are the roof sections 12, 13 which are alternately arranged and which taper inwardly, as shown in Figure 3, that is the sides of the sections 12, 13 will extend 25 radially relative to the tank; also the sides of the sections 12 converge upwardly and the sides of the sections 13 diverge upwardly so that the sides of the alternate sections will fit closely together. These sections are completely enclosed and are buoyant and the sections 13 are, preferably, weighted by being partly filled with water or similar liquid, so that they will be maintained closely seated between the sections 12, as illustrated in Figure 2.

35 The roof sections 12 and 13 do not extend entirely to the center thus leaving a substantially cylindrical opening 14, which is closed by a correspondingly shaped section 15, which is completely enclosed and which has a central downspout 16 extending entirely therethrough and into the tank beneath.

40 The outer ends of the sections 12, 13 converge upwardly to conform to the shape of, and to fit closely against, the inner wall of the trough and the inner ends of said sections converge downwardly. The sides of the section 15 converge downwardly to conform to the contour of, and to fit closely against, the inner ends of the sections 12, 13, as shown in Figure 1.

45 The sections 12, 13 are somewhat narrower vertically than the outer ends thereof and the top and bottom walls of the section 15 are aligned with the corresponding top and bottom walls of the sections 12, 13, so that the section assembly, composed of the sections 12, 13, and 15 presents

a slightly concaved upper and lower face, as clearly shown in Figure 1. The section 15 should be weighted, preferably by liquid therein, so that it will be held firmly in its seat.

The trough is covered by the overlapping plates 17 which are fastened, at their outer ends, to the inwardly turned upper margins of the shoes 6, as shown more clearly in Figure 5, and the inner margins of these plates rest on the upper margin of the inner wall of the trough, as shown in Figures 1 and 5. Therefore water falling onto the roof will be deflected by the plates 17 onto the roof section assembly and will drain to the center and pass through the down spout 16 and, being heavier than the oil, will collect at the bottom of the tank and may be drained off.

If desired the roof sections 12 and 13 may have the bottom surrounding flanges 18 and may be inwardly beveled above the flanges to provide a V-groove around each section and a resilient tube, as 19, may be fitted into each of said V-grooves. These tubes 19 should have relatively thick walls to normally maintain their shape but when the sections are assembled together and pressure applied to them, they will conform to the shape of the groove in which they are located and will form seals between the roof sections as well as between the outer ends of the sections 12, 13 and the inner wall of the trough 5, as clearly shown in Figures 1 and 5. The resilient tubes, or gaskets 7, 8 and 19 thus seal the roof against the escape of vapors from the oil.

The gaskets 19 may, if desired, be dispensed with and the roof sections assembled as illustrated in Figure 2 and thus form substantially leak proof joints.

If the tank is out of plumb the roof hereinabove described may shift correspondingly and the gaskets 7 and 8 correspondingly contract or expand to maintain leak proof joints between the roof and the tank; or if the tank sways due to heavy winds the roof is so mounted that it will adjust itself correspondingly.

It is to be noted that the shoes 6 extend entirely around the tank and move up and down with the roof so as to relieve the tubes, or gaskets 7 and 8 from any frictional contact with the walls of the tank; also a constant outward pressure is exerted against the tank walls to maintain the tank round.

The drawings and descriptions are illustrative merely while the broad principle of the invention will be defined by the appended claims.

What I claim is:

1. A tank roof comprising, an annular trough within, and spaced from, the tank walls, the inner wall of the trough converging inwardly and upwardly, an external annular flange on the lower end of the trough, shoes spaced apart around the trough and in contact with and slideable along, the tank walls, an annular seal around the trough and between it and said shoes and supported on said flange, links flexibly connecting the shoes to the trough, buoyant roof sections assembled within the trough and fitted together and whose outer ends converge upwardly and fit, throughout the area of said outer ends, closely against the inner walls of the trough.

2. A tank roof comprising, an annular trough within, and spaced from, the tank walls, the inner wall of the trough converging inwardly and upwardly, an external annular flange on the lower end of the trough, shoes spaced apart around the trough and in contact with and slideable along, the tank walls, an annular seal around the trough and between it and said shoes and supported on said flange, links flexibly connecting the shoes to the trough, buoyant roof sections assembled within the trough and fitted together and whose outer ends converge upwardly and fit, throughout the area of said outer ends, closely against the inner walls of the trough, said roof sections having grooves around their lower ends and resilient tubes in the grooves forming seals with the adjacent parts of the roof.

PAUL OFFENHAUSER.
